[57] **CLAIM**

The ornamental design for a outdoor video display unit, as shown and described.

DESCRIPTION

FIG. 1 is a right front perspective view of an outdoor video display unit showing our new design;

FIG. 2 is a side elevational view of the outdoor video display unit shown in FIG. 1;

FIG. 3 is an enlarged side sectional view of an outdoor video display unit taken substantially along the line 4—4 of FIG. 2;

FIG. 4 is an enlarged fragmentary side elevational view of an outdoor video display unit shown in FIG. 2;

FIG. 5 is a front elevational view of the outdoor video display unit shown in FIG. 2; and,

FIG. 6 is a fragmentary rear elevational view of the outdoor video display unit shown in FIG. 2.

FIG. 1
